UNITED STATES PATENT OFFICE.

AI B. SHAW, OF MEDFORD, MASSACHUSETTS, ASSIGNOR TO SHAW SPECIALTY CO. INC., OF WEST MEDFORD, MASSACHUSETTS, A CORPORATION OF MASSACHUSETTS.

STOPPER FOR HOT-WATER BOTTLES.

1,423,463.

Specification of Letters Patent. Patented July 18, 1922.

Application filed February 7, 1921. Serial No. 442,968.

To all whom it may concern:

Be it known that I, AI B. SHAW, a citizen of the United States of America, and a resident of Medford, in the county of Middlesex and State of Massachusetts, have invented certain new and useful Improvements in Stoppers for Hot-Water Bottles, of which the following is a specification.

This invention relates to stoppers for hot water bottles and the like and has for its object the production of a device of this character which will prevent leakage through the filling opening when the stopper is properly positioned therein.

15 The invention consists primarily in providing a packing disk so mounted on the stopper that when the packing disk is on its seat the stopper may be rotated without effecting the rotation of said disk.

20 The invention further consists in interposing between said disk and stopper of a metal washer which rotates only with said disk and is adapted to contact with the end of the stopper and prevent the packing disk 25 from being worn by the rotation of the stopper when said disk is non-revolubly positioned upon its seat.

The invention further consists in certain novel features of construction and arrangement of parts which will be understood 30 readily by reference to the description of the drawings and to the claims to be hereinafter given.

35 For the purpose of illustrating the invention, one preferred form thereof is illustrated in the drawings, this form having been found to give satisfactory and reliable results although it is to be understood that the various instrumentalities of which the 40 invention consists can be variously arranged and organized and the invention is not limited to the precise arrangement and organization of these instrumentalities as herein shown and described except as required by 45 the scope of the appended claims.

Of the drawings:

Figure 1 represents a section of the upper portion of a hot water bottle showing applied thereto a stopper embodying the features of the present invention.

50 Figure 2 represents an elevation of the stopper.

Figure 3 represents an elevation of the screw for supporting the packing disk of the stopper.

55

Figure 4 represents a section of a portion of the bottom of the stopper.

Figure 5 represents a section of a metal washer to be mounted on the screw.

Figure 6 represents a section of the packing disk of the stopper, and

Figure 7 represents a section of a smaller washer for clamping the packing disk to the larger washer.

Similar characters indicate like parts throughout the several figures of the drawings.

In the drawings, 10 represents a portion of the upper end of a hot water bottle having embedded therein a threaded socket 11 70 provided at the bottom with the inwardly extending flange 12.

A threaded stopper 13 is adapted to be screwed into the socket 11 by means of a handle 14.

75

Extending through the bottom wall 15 of the stopper 13 is a screw 16 having a head 17 and a threaded shank 18.

The distance between the head 17 and the end of the thread 18 is slightly in excess of 80 the thickness of the bottom 15 of the stopper 13.

The screw 16 is in axial alignment with the stopper 13 and a metal washer 19 is positioned on the threaded end 18 of the shank 85 of said screw 16, said washer being turned on the thread 18 to the extreme end thereof so that no further movement of the washer toward the head 17 is permitted.

The threaded shank 18 also extends 90 through a packing disk 20 of rubber or some similar resilient material and this disk 20 is forced against the face of the washer 19 by the smaller washer 21 threaded to the shank 18 as shown in Figs. 1 and 2 of the 95 drawings.

The head 17 is provided with a screw-driver slot 22 and the shank 18 is similarly provided with a screw-driver slot 23.

The slot 22 is utilized to prevent the screw 100 16 from turning when the washers 19 and 21 are being turned upon the shank 18 in the original installation of the various elements of the stopper.

When the disk 20 is clamped between the washers 19 and 21, said disk 20 is obliged to turn with said washers and with the screw 16 on which said washers are threaded.

The opening 25 in the bottom 15 of the stopper 13 is free from threads or other projections and in this opening 25 the screw 16 is free to rotate.

When the stopper is being turned in the 10 socket 11 no action on the packing disk 20 takes place until said disk comes into contact with the annular flange 12 on said socket 11.

As soon as contact is made between the 15 disk 20 and the flange 12, the friction between the two will prevent the packing disk 20 rotating about its axis relatively to said flange 12, but the stopper 13 may continue to be rotated in the socket 11 thereby jamming 20 the packing disk 20 against the flange 12 and making a perfectly tight fit through which no water can escape.

The jamming of the central portion of the 25 packing disk 20 by means of the smaller washer 21 causes the packing member to be forced against the threads of the screw 16 and makes a non-leakable joint through which none of the water in the bottle 10 can escape.

30 As the washer 19 is interposed between the rubber packing disk 20 and the bottom wall 15 of the stopper 13, when the stopper 13 is turned, the wall 15 will contact with the washer 19 which is of metal and therefore 35 not easily injured.

This interposing of the washer 19 between the packing disk 20 and the bottom of the stopper 13 is a most important feature of the invention as in the turning of the stopper 40 the rubber disk 20 will not be injured by contacting with the bottom wall 15. Moreover when the disk 20 is brought into contact with its seat on the flange 12, it will not be injured by the stopper rubbing in 45 contact therewith.

In the stoppers now in general use the 50 packing disk is secured permanently to the stopper and when the stopper is rotated and the rubber disk is in contact with its seat, the rubbing contact is liable to injure and soon destroy the packing and as there is no ready means of renewing this packing the entire stopper is useless and an entirely new stopper must be provided.

55 In the present invention as soon as the rubber packing disk 20 comes in contact with the flange 12, the friction between these two surfaces is sufficient to prevent the disk from rotating with the stopper and as a consequence there is no injury thereto.

Should the rubber disk deteriorate, it may 60 readily be renewed by inserting a tool, such as a screw-driver in the slot 23 and then removing the smaller washer 21 and packing disk 20.

After this disk 20 has been removed, a new disk 20 may be placed upon the shank 18 of the screw 16 and the locking washer 21 then replaced on the threaded shank 18 and jammed against the packing disk 20.

This simple construction of stopper is most effective in use for it makes the hot water bottle positively non-leakable at this point and the life of the stopper is greatly prolonged.

Moreover, it provides a means whereby a new packing disk may be placed quickly upon the stopper thus making it unnecessary to throw away the body of the stopper.

It is believed that the operation and many 80 advantages of the invention will be understood without further description.

Having thus described my invention, I claim:

1. A hollow threaded bottle stopper having a bottom plate, a headed screw extending through said bottom plate and freely revoluble therein, a packing disk surrounding the shank of said screw, a washer threaded to said screw between said disk and stopper, 90 and means for preventing the displacement of said disk.

2. A threaded bottle stopper having a bottom plate, a headed screw extending through said bottom plate and freely revoluble therein, 95 a packing disk surrounding the shank of said screw, a washer threaded to said screw between said disk and stopper, and another washer threaded to said screw and adapted to prevent the displacement of said disk.

3. A threaded bottle stopper having a bottom plate, a headed screw extending through said bottom plate and freely revoluble therein, a packing disk surrounding the shank of said screw, a washer threaded to said screw 105 between said disk and stopper and permitting slight end movement of said screw, and means for preventing the displacement of said disk.

4. A hollow threaded bottle stopper having a bottom plate, a headed member extending through said bottom plate and having a slot in its outer end, a packing disk on said member, a washer threaded to said member between said disk and stopper, and a second washer threaded to said member on the opposite side of said disk and adapted to be moved endwise of said member and relatively to the first-mentioned washer to clamp said disk and insure its rotation with said threaded member.

5. A cylindrical threaded bottle-stopper having a bottom wall with a central opening; a headed member disposed within said opening with a threaded shank extending outwardly from said bottom wall; a washer threaded to said shank; a metal washer also threaded to said shank; and a packing member clamped between said washers.

6. A cylindrical threaded bottle-stopper

having a bottom wall with a central opening; a threaded member loosely mounted in said opening and prevented from displacement by a head on said member disposed within said stopper; a metal washer rigidly mounted on said threaded member and adapted to rotate freely relatively to said bottom wall; a smaller clamping washer also rigidly mounted on said threaded member;

and a packing member clamped between said 10 washers.

Signed by me at 746-7 Old South Bldg., Boston, Mass., this 4th day of February, 1921.

AI B. SHAW.
